UNITED STATES PATENT OFFICE.

EDWARD E. ASHLEY, JR., OF DARIEN, CONNECTICUT, ASSIGNOR TO ELEVATOR SUPPLIES COMPANY, INC., A CORPORATION OF NEW JERSEY.

DESIGN FOR AN ELEVATOR-POSITION INDICATOR OR SIMILAR ARTICLE.

Application filed December 19, 1925. Serial No. 15,787. Term of patent 14 years.

To all whom it may concern:

Be it known that I, EDWARD E. ASHLEY, Jr., a citizen of the United States, residing at Darien, in the county of Fairfield and State of Connecticut, have invented a new, original, and ornamental Design for an Elevator-Position Indicator or Similar Article, of which the following is a specification, reference being had to the accompanying drawings, forming part thereof, wherein—

Fig. 1 is a front elevation view of the article, showing my new design;

Fig. 2 is a cross-sectional view taken along line 2—2 of Fig. 1;

Fig. 3 is a cross-sectional view taken along line 3—3 of Fig. 1.

I claim:

The ornamental design for an elevator position indicator or similar article, as shown.

EDWARD E. ASHLEY, JR.
